ICE TRAY

Logan L. Mallard, Norfolk, Va., assignor of one-half to H. Clay Hofheimer, II, Norfolk, Va.

Application November 21, 1939, Serial No. 305,552

10 Claims. (Cl. 62—108.5)

This invention relates to ice cube trays of the type which includes the incorporation of means for removing the ice cubes.

One of the objects of the invention is to provide cube separating and removing means which stress the individual cube masses to move them relative to one another for breaking the bond between them and the tray and tray partitions, through the instrumentality of cams frozen into the cubes and which act against the corresponding cam surfaces of the recesses in which the cams are imbedded.

Another object of the invention is the provision of a cube separating and removing unit, removable as a whole from the tray and comprising a longitudinal partition loosely carrying a plurality of transverse partitions tiltable along horizontal axes remote from the top edges, and preferably at their bottom edges, with an actuating member slidable longitudinally of the longitudinal partition having cams projecting downward between the transverse partitions to a depth below the liquid level in the tray, having freedom of movement relative to the transverse partitions whereby the latter are tilted not directly by mechanical contact of the cams, but through the intermediary of the ice masses between said cams and the upper parts of said transverse partitions, so that due to their mechanical disconnection from the actuating member, said transverse partitions are free to oscillate in a more or less desultory manner relative to one another when the bond is broken between them and the intervening ice masses, permitting the ice cubes to freely fall, and preventing their hanging between the transverse partitions.

A further object of the invention is the provision of a cube separating unit as described, in which the cams resolve the actuating force into two components, one of which is expended in tilting the cubes against and relative to the transverse partitions, and the other of which acts downwardly, forcing the cubes downward between said partitions.

Another object of the invention is the provision of a cube separating unit as described, which first employs the ice cubes at one end of the tray as a fulcrum for tilting the rest of the ice mass, including the partitions, en bloc relative to the tray, thus breaking the adhesion of the ice with the sides and bottom of the tray, and then through the action of the mechanical cams against the correlated ice cam surfaces within the cubes, forcing the said end cubes away from the surfaces of the tray which they contact, and

tilting the rest of the ice cubes against and relative to the transverse partitions, breaking their bonds with the transverse partitions through shearing movement, and forcing them downward between said partitions.

5 A further object of the invention is to provide a cube separating unit as described, in which the actuating member is a channel, the cams of which project downwardly in pairs on opposite sides of the longitudinal partition and having shoulders facing in the direction of the retrogressive movement of said actuating member engageable with the transverse partitions for positively aligning them in parallel planes when the unit is placed in the tray before freezing to determine a uniform shape for the ice cubes.

20 Still another object of the invention is to provide the cube separating unit with an actuating handle having initial freedom of movement whereby it may be lifted to a convenient angular position relative to the actuating member, for grasping, without encountering the resistance of the ice.

25 Another object of the invention is the provision of a cube separating unit removable as a whole from the tray, consisting of a longitudinal partition loosely carrying a plurality of transverse partitions, tiltable along horizontal axes remote from their top edges, and preferably at their bottom edges, with an actuating member slidable longitudinally of the longitudinal partition having cams projecting downwardly below the transverse partition to a depth below the liquid level in the tray, having freedom of movement relative to the transverse partitions whereby the latter are tilted indirectly through force transmitted through said cams and the intervening ice masses to said transverse partitions for producing the shearing movement between the ice cubes

30 40 45 50 55 and said transverse partitions and wherein the cam at one end is pivotally connected to an operating handle, said handle performing the cube separating and ejecting function through an arcuate movement in one direction which may be differentiated into three parts, an initial movement in which the handle can be freely raised to a convenient grasping angle without encountering ice resistance, a further movement in which said handle operates the pivoted cam as a fulcrum against the end ice cubes for lifting the rest of the ice mass, and including the transverse partitions, en bloc and for moving the said fulcrum cubes in a translatory manner relative to the tray surfaces which they contact, the third or final movement of the handle sliding the actu-

ating member and causing the fixed cams to act against their correlated ice cam surfaces to tilt the transverse partitions producing shearing movement between said partitions and the intervening ice cubes, and to force said ice cubes downwardly relative to said partitions.

Still another object of the invention is to provide an ice tray of the class described, in which the resistances offered by the adherent ice are attacked progressively, so that a child can separate and remove the cubes without undue effort, and in which the cubes can be separated and removed in a sanitary manner without it being necessary to touch the ice with the hand.

A further object of the invention is to make an ice tray as described, in a simple and inexpensive manner, and so constructed as to be capable of economic mass production.

Other objects of the invention will appear as the following description of a preferred and practical embodiment thereof proceeds.

In the drawing which accompanies and forms a part of the following specification, and throughout the several figures of which the same characters of reference have been employed to designate identical parts:

Figure 1 is a perspective view of an ice tray embodying the principles of the subject invention;

Figure 2 is a longitudinal section taken along the line 2-2 of Figure 1;

Figure 3 is a cross-section taken along the line 3-3 of Figure 1;

Figure 4 is a perspective view showing a transverse partition or fin in separated relation to the longitudinal partition;

Figure 5 is a perspective view showing a slightly modified form of the longitudinal partition.

Referring now in detail to the several figures, the numeral 1 represents the ice tray which may be of conventional shape and construction, being slightly flared at the ends 2 and 3. The cube separator and lifter is a unitary structure consisting of the longitudinal tray partition 4 and the transverse tray partitions or fins 5. The transverse partitions are loosely carried by the longitudinal partition in such a manner as to tilt on a horizontal axis which is located at some point other than adjacent the top edges of said transverse partitions. As shown, the partitions 5 pass through substantially triangular slots 6 formed at equal intervals along the longitudinal partition 4. Said slots extend about half way up the partition 4, and the transverse partitions 5 are provided in their upper edges with the median slots 7, the latter embracing the portion of the longitudinal partition about the slots 6. The bottom of the triangular slots 6 is preferably just about the width of the material of the transverse partitions 5, so that the latter can swing about a horizontal axis which passes through the bottom wall of the slots 6. The transverse partitions can be introduced into the slots 6 in any suitable manner, but the disclosure suggests that the longitudinal partition 4 shall be formed with slits 8 extending from its lower edge into the slots 6 which slits can be temporarily opened for the insertion of the transverse partitions by forcibly deflecting the metal of the longitudinal partition 4 on either side of the slits 8 so as to open them. The resiliency of the metal may be relied upon to restore the longitudinal partition to its planiform shape after the insertion of the transverse partitions 5; or the metal at the sides

of said slits can be sufficiently deflected in the opposite direction to accomplish this purpose. The transverse partitions 5 are preferably provided with short median slots 9 indenting their bottom edges and adapted to embrace the portion of the longitudinal partition which lies below the slots 6.

An actuating member 11 is slidably mounted upon the top of the longitudinal partition 4. This actuating member has the form of a channel with its middle portion or web overlying the longitudinal partition 4, and being formed with longitudinal slots 12 which receive the upstanding lugs 13 formed on the upper edge of the longitudinal partition 4. The slots 12 are longer than the lugs 13 so as to provide a range of sliding movement of the actuating member 11 relative to the longitudinal partition. The lugs 13 are headed in any suitable manner as by a washer, and riveted so as to permanently attach the actuating member 11 to the partition structure.

The flanges 14 and 15 are cut away, forming notches 16 at the points where the actuating member overlies the transverse partitions 5 so as to provide freedom of movement between the actuating member and the transverse partitions. The flanges are also provided, between the several transverse partitions and between the final transverse partition and the end of the tray adjacent one end thereof with fixed cams 17. These cams project downwardly below the liquid level in the tray 1. The forward faces of said cams slope upwardly and forwardly.

A handle 18 overlies the actuating member 11 preferably lying flat against said actuating member when the cube separating and lifting mechanism is in repose position. Said handle is of two-part construction, being pivotally connected at 19 to a sturdy shank 20, which at one end carries a cam 21 pivotally mounted at 22 to the longitudinal partition. It will be understood that the forward portion of the shank 20 is bifurcated, as indicated at 23, and that the cam 21 is duplicated on opposite sides of the longitudinal partition. The shank 20 passes through a hole 24 in the actuating member 11 and abuts against the forward edge 25 of said hole for imparting slidable movement to the actuating member 11.

The handle 18, for the sake of rigidity, is provided with the lateral flanges 26 and 27. These flanges adjacent the pivoted end of said handle are provided with undeturned lugs 28 forming a strap. The shank 20 is provided with a narrowed portion 29 extending into the space defined within said handle by the undeturned lugs 28, with lost motion, so that the handle 26 can be readily lifted through a small angle relative to the actuating member to facilitate its being grasped, without encountering any ice resistance.

A characteristic feature of the subject invention is that the cams 17 do not directly contact the transverse partitions 5, for tilting them, at any time during the reciprocatory movement of the actuating member. This leaves the transverse partitions 5, which are loosely mounted with respect to the longitudinal partition, free to oscillate in a desultory manner relative to one another for the purpose of permitting the cubes to drop from between the transverse partitions without binding between them, as is generally the case where the transverse partitions are rigidly parallel to one another.

The cams 17 are provided rearwardly with the extensions 30, which when the actuating member

is in its retrogressive position, contact the transverse partitions, holding them rigidly in parallel planes. This position of parts is automatically assumed when the handle is placed in its position of repose flat upon the top of the actuating member 11.

In operation, the parts being in the position shown in Figure 2, the tray is filled with water and placed in the refrigerator. It will be noted at this time that all of the cams 17 as well as the cam 21, extend below the water level in the tray. The water is then frozen solidly into ice. The cams which are imbedded in the ice, thus mold for themselves cooperating ice cam surfaces.

In the separation and removal of the ice cubes, the handle 18 is first lifted through the small initial angle permitted by the lost motion at the point 31 between the thin part 29 of the shank 20 and the strap formed by the undeturned lugs 28. The handle is moved up a little further, rotating the cam 21 about the pivot 22. The surface of the cam 21 is eccentric to the pivot 22, so that the first result of the rotation of this cam against its correlated ice cam surface will be to utilize the two end cubes engaged by the cams 21, as a fulcrum, causing the upward tilting of the rest of the ice in the tray, exclusive of the said two end cubes, en bloc with the embedded transverse partitions 5. This lifting takes place progressively from the left hand end 32 of the ice block, breaking the adhesions of said block with the bottom and side walls of the tray, and of course, shearing the ice blocks from the two end cubes which are serving as a fulcrum. The tilting or lifting of the ice block and the rotation of the nose 33 of the cam 21 away from the adjacent transverse partition 5 makes room for the longitudinal movement of the end cubes being pressed upon, and as the eccentric cam 21 is rotated further, it will press laterally against its correlated ice cam surface in a direction to force the end cubes away from the adjacent end wall and side walls of the tray, thus breaking their adhesions to said end and side walls and setting them free.

The lifting of the ice block from the bottom of the tray and the creation of space longitudinally of said tray by the lifting of said ice block gives room for the tilting of those ice cubes which still remain en bloc. This tilting is accomplished in the following manner.

When the handle is moved to a position in which the shank 20 engages the edge 25 of the actuating member, the latter is then slidably moved toward the left, as viewed in Figure 1, causing the cams 17 to move forwardly against their correlated ice cam surfaces, tilting the cubes forcibly against the transverse partitions which are in a forward position with respect to said cubes, and tilting said partitions, thereby producing a shearing movement between the partitions and cubes which breaks the adhesion of said cubes to said transverse partitions.

It will be noted that the forward faces 34 of the cams 17 slope forwardly and upwardly, so that when they engage the forward ice cam surfaces, the transmitted force is resolved into two components, only one of which is employed in tilting the cubes and tilting the transverse partitions, the other component acting downwardly and thrusting the cubes downwardly relative to the actuating member. As has been previously stated, the fact that there is no direct mechanical contact between the cams 17 and the transverse partitions, permits the latter to freely wobble or

oscillate about an approximately vertical axis, so that the cubes when being ejected downwardly, will not bind between adjacent transverse partitions, but will fall freely from between the confining walls of the ice cube separating and removing unit.

Inasmuch as the said unit is rigidly frozen with respect to the tray, the initial functioning of the device can be accomplished without any attempt to hold the unit in place in the tray. After the ice mass, excluding the end cubes which act as a fulcrum, has been broken away from the tray, it is necessary to hold the unit down to the tray for accomplishing the final individual separation of the ice cubes. So easy is the action of the device, however, that it is merely necessary to place the hand lightly upon the top of the actuating member while reciprocating said member. This enhances the sanitary value of the device, as it is unnecessary ever to touch the ice cubes with the hand.

The fact that the cams 17 and 21 operate from within the ice cubes rather than upon the ice cubes, makes it possible to separate the ice cubes intact substantially without shattering.

In Figure 5, I have shown a modified form of the invention, in which the triangular slot 6 of the longitudinal partition 4 opens in the lower edge of said longitudinal partition with a width sufficient to permit the insertion of the transverse partition 5. The longitudinal partition is provided adjacent the sides of the open end of this slot with extensions or titts 35, which can be upset or riveted together after the transverse partition is in place to occlude the end 9 of said slot and retain the transverse partition in place.

From the above, it will be understood that I have provided an improved ice cube tray of the type which includes the incorporation of means for separating and removing the cubes, which is simple in construction, easy to operate, and which lends itself to economical mass production. It provides a device of the character described, which attacks the ice resistances progressively, and in a novel manner, requiring so little force as to be easily within the scope of effort of a small child. This very ease of operation also minimizes the strains to which the mechanical elements are subjected, thus prolonging the life of the apparatus and minimizing the necessity for repair.

While I have in the above description disclosed what I believe to be a preferred and practical form of the invention, it will be understood to those skilled in the art that the specific details of construction and arrangement of parts as shown and described are by way of example, and not to be construed as limiting the scope of the invention defined in the appended claims.

What I claim as my invention is:

1. In combination with an ice cube tray having ice cubes frozen therein, cube separating means therefor comprising a longitudinal tray partition and transverse tray partitions carried thereby, and tiltable through a small angle about horizontal axes remote from the top of said transverse partitions, means for providing longitudinal tilting movement of said cubes in said tray and the intervening transverse partitions to produce shearing movement between said cubes and partitions, and means for tilting said cubes and said partitions comprising cams frozen into said cubes out of contact with said transverse partitions and movable longitudinally so as to coact with their correlated ice cam surfaces, the bottom sur-

faces of said cams being substantially normal to said partition.

2. In combination with an ice cube tray, cube separating means therefor comprising a longitudinal tray partition and transverse tray partitions carried thereby, tiltable through a small angle about horizontal axes remote from the top of said transverse partitions, an actuator mounted to slide longitudinally of said longitudinal partition having pairs of fixed cams depending on opposite sides of said longitudinal partition below the liquid level in said tray, into each of the cube molds defined by said partitions and the tray walls, except the molds at one end of said tray, said fixed cams having free movement with respect to said transverse partitions throughout the range of movement of said actuator in a cube separating direction, an operating handle comprising a rigid portion straddling the longitudinal partition and pivoted thereto in the zone of the said end molds and having eccentric cams at its lower end on opposite sides of said longitudinal partition and depending below the liquid level in said tray, said rigid portion passing through a slot in said actuator and being engageable with the front end of said slot with lost motion whereby it turns the eccentric cams prior to sliding the actuator, said handle including a grasping portion pivoted to said rigid portion with limited lost motion, having a position of repose in which it lies flat upon said actuator and being tiltable upwardly through a convenient angle for grasping, without encountering ice resistance.

3. In combination with an ice cube tray, cube separating means therefor comprising a longitudinal tray partition and transverse tray partitions carried thereby, mounted in upwardly flaring slots in said longitudinal partition and loosely retained therein, and tiltable through a small angle about horizontal axes remote from the top of said transverse partitions, an actuator mounted to slide longitudinally upon said longitudinal partition having pairs of fixed cams depending on opposite sides of said longitudinal partition below the liquid level in said tray into each of the cube molds defined by said partitions and the tray walls, except the molds at one end of said tray, said fixed cams having free movement with respect to said transverse partitions throughout the range of movement of said actuator in a cube separating direction, an operating handle comprising a rigid portion straddling the longitudinal partition and pivoted thereto in the zone of the said end molds, having eccentric cams at its lower end on opposite sides of said longitudinal partition and depending below the liquid level in said tray, said rigid portion passing through a slot in said actuator and being engageable with the front end of said slot with lost motion, whereby it turns the eccentric cams prior to sliding the actuator, and being engageable with the rear end of said slot with lost motion for moving said actuator retrogressively, all of said cams having portions engageable with said transverse partitions when said actuator is retrogressively moved for aligning said transverse partitions in parallel planes, said handle including a grasping portion pivoted to said rigid portion with limited lost motion, having a position of repose in which it lies flat upon said actuator, and being tiltable upwardly through a convenient angle for grasping without encountering ice resistance.

4. In combination with an ice cube tray 75 mounted to slide longitudinally of said longitu-

adapted to have ice cubes frozen therein, cube separating means therefor comprising a longitudinal tray partition, transverse tray partitions carried thereby and tiltable through a small angle about horizontal axes remote from the top of said transverse partitions, and an actuator mounted to slide longitudinally of said longitudinal partition and having cams adapted to depend below the unfrozen liquid level in said tray 10 and into each of the cube molds defined by said partitions and by the tray walls, said cams having free movement with respect to said transverse partitions throughout the range of movement of said actuator in a direction adapted to release the cubes, said cams being adapted to coact with the respectively adjacent ice cam surfaces within the cubes, the movement of said actuator in a cube releasing direction being adapted to tilt the cubes and said transverse partitions by force transmitted to said partitions through the cubes, the bottom surfaces of said cams being substantially normal to said partition.

5. In combination with an ice cube tray adapted to have ice cubes frozen therein, cube separating means therefor comprising a longitudinal tray partition, transverse tray partitions carried thereby and tiltable about horizontal axes remote from the top of said transverse partitions, and loosely mounted for desultory oscillation about approximately vertical axes, and an actuator mounted to slide longitudinally of said longitudinal partition and having cams adapted to depend below the unfrozen liquid level in said tray into each of the cube molds defined by said partitions and by the tray walls, said cams being adapted to have free movement with respect to said transverse partitions throughout the range of movement of said actuator in a direction adapted to release the cubes, said cams having means engageable with said transverse partition for aligning them in planes approximately parallel with each other when said actuator reaches the limit of its movement in the opposite direction, said cams being adapted to coact with the respectively adjacent ice cam surfaces within the cubes when said actuator is moved in a cube releasing direction, said movement being adapted to tilt the cubes and said transverse partitions by force transmitted to said partitions through the cubes, the bottom surfaces of said cams being substantially normal to said partition.

6. The combination of claim 4 wherein the forward faces of said cams are upwardly inclined in the direction of the cube releasing movement of said actuator.

7. The combination of claim 5 wherein the forward faces of said cams are upwardly inclined in the direction of the cube releasing movement of said actuator.

8. The combination of claim 5 wherein said cams are arranged in pairs adapted to depend on opposite sides of said longitudinal partition below the unfrozen liquid level in said cube molds, said cams having means engageable with said transverse partitions on opposite sides of said longitudinal partition for the alignment of said transverse partitions.

9. In combination with an ice cube tray adapted to have ice cubes frozen therein, cube separating means therefor comprising a longitudinal tray partition, transverse tray partitions carried thereby and tiltable through a small angle about horizontal axes remote from the top of said transverse partitions, and an actuator 70 mounted to slide longitudinally of said longitu-

dinal partition and having fixed cams adapted to depend below the unfrozen liquid level in said tray and into each of the cube molds defined by said partitions and the tray walls with the exception of the cube molds at one end of said tray, said fixed cams being adapted to have free movement with respect to said transverse partitions throughout the range of movement of said actuator in a direction adapted to release the cubes, an operating handle pivoted to said longitudinal partition and engageable with said actuator and being adapted to move said actuator after an initial period of lost motion, in a direction adapted to release the cubes, an eccentric cam on said handle in the zone of said end molds and adapted to depend below the unfrozen liquid level in said tray, said eccentric cam being adapted to coact with the respectively adjacent ice cam

surfaces within the cubes in said end molds, the bottom surfaces of said cams being substantially normal to said partition.

10. The combination of claim 9 that includes an operating handle pivoted to said longitudinal partition and engageable with said actuator in a manner adapted to move said actuator in a direction adapted to release said cubes, after an initial period of lost motion, an eccentric cam on said handle in the zone of said end molds adapted to depend below the level of the unfrozen liquid in said tray, said eccentric cam being adapted to be engageable with adjacent ice cam surfaces within said end cubes and to act 15 against said end cubes as a fulcrum prior to the movement of said actuator.

LOGAN L. MALLARD.
